UNITED STATES PATENT OFFICE

147,814

DESIGN FOR A BATTERY CHARGER OR SIMILAR ARTICLE

Merlin L. Pugh, Minneapolis, Minn.

Application October 24, 1945, Serial No. 123,132

Term of patent 7 years

(Cl. D26—5)

To all whom it may concern:

Be it known that I, Merlin L. Pugh, a citizen of the United States and a resident of Minneapolis, in the county of Hennepin and State of Minnesota, have invented a new, original, and ornamental Design for a Battery Charger or Similar Article, of which the following is a specification, reference being had to the accompanying drawing, forming part thereof.

Figure 1 is a front perspective view of a battery charger showing my new design.

Figure 2 is a rear perspective view of the battery charger.

The dominant features of my design reside in the portions shown in full lines.

I claim:

The ornamental design for a battery charger or similar article, substantially as shown and described.

MERLIN L. PUGH.
